INVENTOR

Emil B. Miller

BY

James Sheehan & Co., ATTORNEYS.

UNITED STATES PATENT OFFICE.

EMIL B. MILLER, OF SCHULENBURG, TEXAS.

LIQUID-DISPENSING APPARATUS.

1,376,348.

Specification of Letters Patent. Patented Apr. 26, 1921.

Application filed October 7, 1919. Serial No. 329,143.

To all whom it may concern:

Be it known that I, EMIL B. MILLER, a citizen of the United States, residing at Schulenburg, in the county of Fayette and State of Texas, have invented new and useful Improvements in Liquid-Dispensing Apparatus, of which the following is a specification.

My present invention pertains to liquid dispensing apparatus, and it contemplates the provision of a device of the character set forth whereby gasolene and the like may be dispensed to autoists without the employment of an assistant or helper.

The invention further contemplates a liquid dispensing apparatus that is simple and positive in action and one that is not liable to become inoperative after a short period of use. The device is what might be termed a self-selling gasolene station.

The invention in all of its detail will be fully understood from the following description and claim when the same are read in connection with the drawings accompanying and forming part of this specification in which:

Figure 1, is a sectional view illustrating the gears, governor, etc., that I employ in my device.

Fig. 2, is a detail of the valve employed in the gasolene supply pipe.

Similar numerals of reference designate corresponding parts in all of the views of the drawings.

As clearly appears in the drawings, my novel liquid dispensing apparatus comprises a tank 7 for gasolene or the like and said tank may be and preferably is located below the level of the ground. The tank is of the usual construction and may be provided with a filling aperture. However, the tank *per se* forms no part of my invention and hence any type of tank or container may be used.

At one end of said tank I provide a conduit 5 that extends approximately to the bottom of the tank 7 and is secured thereto by a collar 6 and at its upper end the pipe 5 is connected to a valve casing 4. The valve 4 is of the well known construction and comprises (as illustrated in Fig. 5) a stem 92 and a head 93; the said stem 92 being surrounded by a spring 94 that is housed within the valve casing 4 and a nuts

at its lower end against the head 93. At 55 its extreme upper end the stem 92 has a member 92' that rests in and is confined by an eye 9" of the arm 9. The head 93 of the stem 92 will, under normal conditions rest in the seat formed in the casing 4 and hence prevent the flow of liquid from the tank 7.

The valve 4 is provided with a conduit 90 that extends at a right angle to and communicates with the conduit 5 and said conduit 90 terminates in an upwardly extending conduit 3 that enters an auxiliary tank 1 at the lower end of said tank. The said tank 1 is further provided with a flexible hose 2 and a stop-cock 2' the purpose of 65 70 which will be apparent during the further disclosure of my invention.

The reservoir or tank 7 is, in order to ascertain the amount of air pressure contained in said reservoir, provided with a 75 gage 12, of well known construction having the tube 70 connected with the tank 7 at its upper end.

In order to prevent unscrupulous persons from surreptitiously removing liquid from 80 the tank 7, I place the valve 4 and its appurtenances as also the gage 12 within a casing 13; said casing being hinged at 42 and secured at 41 with a lock of any form and construction and as clearly appears in 85 Fig. 1 the conduit 3 and hence tank 1 are prevented from casual displacement by the bracket 13' that is secured to the casing or housing 13.

Immediately in rear of the casing 13, I 90 provide a housing or casing for the operating mechanism of the device, the said housing comprising a top wall 19, bottom wall 27 and side walls 14 and 20; the housing or casing 13 being secured to the wall 95 14 as illustrated.

Within the casing formed by the walls 14, 19, 20 and 29 I secure the operating mechanism of the device which comprises a shaft *a* having a governor of the "Picketting" type consisting of the arms 41', wheel 40' and the revolving balls 18.

In order to increase or reduce the speed of the governor when occasion demands, I provide the thin screw 40 having a wheel 100 or brake 40" that engages the wheel 40' of the governor.

At its opposite end to that on which the

wheel 40' is provided, the shaft *a* has a toothed wheel 17 that engages the gear 16. The shaft *d* is also provided with a toothed gear wheel 16' that in turn engages the 5 toothed gear wheel 15 of a shaft *e*; said shaft *e* being also provided with a toothed gear wheel 15'; that engages a toothed gear wheel 10 of the shaft *f*. At *b* I provide a shaft having a toothed gear wheel 34 that 10 also engages the teeth 15 of the shaft *e*. The shaft *f* has a housing 33 and at one side of the said housing is a ratchet wheel 41 and engaging said ratchet wheel 41 is a pawl 43.

15 Secured to the shaft *f* within the housing is a coil spring (not shown) and depending from said shaft is a lever 50 having a weight 35'.

20 By reference to Fig. 1 it will be seen that below the shaft *b* I provide a shaft *c* having a disk 33' and said disk is provided with a projection 36 and notch 36' for an important purpose hereinafter set forth.

25 The shaft *c* derives motion from the shaft *b* and imparts said motion to the disk 33'.

30 Arranged in the casing is an arm 29' secured thereto in movable manner by the brace 29. A connection 30, having the short arm 31, is secured to said arm 29' and extending at approximate right angles and in connection with the arm 31 is an arm 32 secured to the lower wall 27 of the casing by a spring 28. At its inner end the arm 32 is provided with a dog that rests in the notch 36 of the disk 33'.

35 Resting in the groove 36 of said disk 33' is the member 9' of the arm 9 and said arm 9 is secured to the casing wall 14 by a guide member 4' as shown and is thence extended 40 through the wall 14 and secured to the stem 92 as before described.

45 At its forward end the arm 29' is provided with a coin actuated plate 26.

Secured to the front wall 20 of the casing 50 is a housing having a hinged lid 21 and a keeper 25 and lock 24 and in said lid 21 is a coin aperture 22 having a guideway chute 23.

55 In order to wind the spring of the shaft *f* the handle 50 is secured to the outer end of said shaft.

60 In the practical operation of the device, gasoline or other fluid is placed in the reservoir 7 and the spring of the shaft *f* is placed under tension by rotation of the handle 50.

55 When it is desired to obtain fluid from the device, a coin *C* is placed in the slot 22 and will be caused to travel down the guideway 23 and fall upon the plate 26. The arm 29' will thus be moved downwardly and will 65 impart a motion to the arm 32 and release the dog 35 from the notch 36'. This will permit the disk 33' to rotate and the portion 9' to become unseated from its seat.

65 By reason of the governor of shaft *a* and the spring and gears of the shafts *b*, *c*, *d*, *e*

and *f* the organized mechanism will be placed in operation.

Rotation of the disk 33 will cause the arm 9 to raise and hence the valve will be unseated and permit fluid to pass from the 70 tank 7 to conduits 5, 11 and 3 into auxiliary tank 1 where it may be drawn off by manipulation of the cock 2' of hose 2.

It is evident that the disk 33 controls the 75 amount of liquid dispensed, and hence by decreasing the size of the disk, a smaller amount of fluid will be dispensed and by increasing the size a larger amount may be dispensed.

In order to cause liquid to flow from the 80 tank 7, when occasion demands, it will simply be necessary to operate the hand pump 69 in the well known manner and thereby exert a certain amount of pressure on the 85 contents of the tank.

90 In order to prevent a person from inserting a piece of wire or the like into the coin slot and thereby operate the device, the coin slot may be arranged in a staggered manner.

I would distinctly have it understood that 95 the coin-actuated apparatus described and shown in connection with my dispensing apparatus, forms no part of my invention, but is simply used for the purpose of illustration.

99 Having described my invention, what I claim and desire to secure by Letters-Patent is:—

100 In a coin actuating apparatus, the combination of a liquid reservoir, a conduit extending into the reservoir, a valve arranged in the upper end of the conduit, a conduit extending at right-angles from the valve and then upward, an auxiliary reservoir secured to the upper end of the last-named 105 conduit, a casing arranged around the valve, a stem secured to the valve head, a lever secured to the stem and entering the casing and having a bent end opposite the end 110 secured to the stem, a spring actuated disk having a notch that normally receives the bent end to preclude downward movement of the lever that is secured to the stem; a second notch provided in the disk, a short arm fulcrumed in the casing and having a 115 bent end that normally rests in the last named notch and a comparatively long arm secured to the short arm whereby on downward movement of the long arm the notch of the short arm will be displaced from the 120 notch of the disk to permit rotary motion of said disk.

125 In testimony whereof I have hereunto set my hand in presence of two subscribing witnesses.

EMIL B. MILLER.
